UNITED STATES PATENT OFFICE.

JOHN P. NEFF, OF EAST ORANGE, NEW JERSEY, ASSIGNOR TO AMERICAN ARCH COMPANY, OF NEW YORK, N. Y., A CORPORATION OF DELAWARE.

ARCH CONSTRUCTION FOR SHALLOW FIRE-BOXES.

1,229,392.

Specification of Letters Patent. Patented June 12, 1917.

Application filed February 24, 1916. Serial No. 80,311.

To all whom it may concern:

Be it known that I, JOHN P. NEFF, a citizen of the United States, and a resident of East Orange, county of Essex, and State 5 of New Jersey, have invented certain new and useful Improvements in and for Arch Construction for Shallow Fire-Boxes, of which the following is a specification.

My invention relates to improvements in 10 the arches of locomotive boilers of the shallow firebox type, and has special reference to arch constructions for the fireboxes of Wooten boilers which have firebox extensions or barrel combustion chambers forward of the grate.

The firebox of a Wooten type boiler differs from others chiefly in the matter of its height. The distance between the grate and the crown sheet is much less than in locomotive fireboxes of other types. The reason of 20 this peculiarity is that Wooten fireboxes are designed for use with anthracite coal; a fuel which yields a very short flame, as compared with others, and which therefore necessitates the arrangement of the chief heating surface (the crown sheet) close to the fuel bed. The height of the firebox extension, sometimes called the barrel combustion chamber, is determined by the height 30 of the crown sheet as in other fireboxes. Another characteristic of a Wooten firebox is that the grate is placed almost on a level, with the floor of the extension.

It is claimed for the Wooten type firebox 35 that by reason of its low height there is a substantially equal distribution of the hot gases in the flues of the boiler; and that this and the attendant easy maintenance of the flues and the flue sheet, are advantages secured without material loss of heating value 40 in the walls of the firebox, inasmuch as the latter are close to the fuel bed. Against the attendant advantages of such fireboxes, I find that the flow of hot gases from grate 45 to flues is so rapid and direct that the rear part of a Wooten firebox is much less effective than supposed.

It has been suggested that a cure may be effected by providing Wooten fireboxes with 50 inclined refractory arches of the kind used in bituminous coal-burning locomotives but in the past there have been no practical means of installing such arches in Wooten fireboxes. The narrowness or lack of depth 55 in the throat sheets of such boilers has prac-

tically prohibited the use of arch tubes and, on the other hand, the width of such fireboxes has prevented the use of arches supported from the side sheets.

The object of my invention is to provide 60 within a Wooten type firebox a refractory tube-supported arch which shall perform the same desirable functions as those which are used in bituminous coal-burning fire- 65 boxes.

The manner in which I attain this object, and the nature and particulars of my invention, will be understood on reference to the drawings that form part of this specification, and in which:—Figure 1 is a longitudinal section of a Wooten type locomotive boiler embodying my invention;—Fig. 2 is a transverse section thereof on the line X—X of Fig. 1;—Fig. 3 is a horizontal section on the line Z—Z of Fig. 1;—Fig. 4 is 70 a perspective detail illustrating the non-interfering intersection portions of two of the transverse arch tubes;—Fig. 5 is a longitudinal section showing a modification of 75 my invention;—Fig. 6 is a section on the line W—W of Fig. 5;—and, Fig. 7 is a section on the line V—V of Fig. 5.

The familiar parts of a Wooten type firebox are as follows:—The boiler-barrel 2;—the firebox shell, 3;—the mud ring, 4;—the 85 side sheets, 5, 5;—the crown sheet, 6;—the rear sheet, 7;—side water legs, 8, 8;—the rear water legs, 9;—the fuel door, 10;—and inner throat sheet, 11;—the shallow front water leg, or throat, 12;—the flue sheet, 90 13; and, the flues, 14. The grate, 15, usually occupies the whole space within the confines of the mud ring, extending from side to side of the firebox and from the rear sheet, 7, to the throat sheet, 11.

The firebox-extension or barrel combustion chamber, B, is all that part of the firebox between the flue sheet, 14, and the throat sheet, 11. The floor, 16, and sides, 16', of the extension, B, join the extension, 6', of 100 the crown sheet which forms the top of the extension.

It will be noted that a Wooten firebox is of much less height than width. Instead of attempting to employ a refractory arch extending upwardly and rearwardly from the lower part of the throat sheet, 11, I first divide the firebox into fire and combustion chambers by means of a refractory cross wall, 17, in the mouth of the firebox-exten- 105 110

sion, B. I then construct an overhanging arch rearwardly of the wall by means of arch tubes, 18, extending from side sheet to side sheet with refractory bricks, 19, placed 5 on said tubes. The wall, 17, may rise to the center of the combustion chamber, B, or even higher if desired. This wall will be described in detail hereinafter. It serves to partly separate the combustion chamber from the firebox. But this amount of separation is not sufficient to insure the best results. Such results can only be attained through the employment of a large mass of refractory bricks 15 in the form of an arch which extends rearwardly from the wall, 17, and overhangs the grate of the firebox. Most conveniently, the mass is composed of a large number of refractory bricks, 19, all of a size to be passed through the fuel door, 10.

20 Primarily, I arrange the refractory bricks, 19, in rows which extend transversely across the upper part of the firebox. These transverse rows are preferably separate from one another to the extent necessary to prevent 25 the fusing together of the ends of the bricks. The arch measured rearwardly from the wall, 17, may be of any desired length. As a rule, four transverse rows of bricks make an arch of sufficient length to insure the movement of the firebox gases rearwardly and thence forwardly upon the crown sheet, as required to overcome the objectionable features of an open Wooten firebox.

For supporting the transverse rows of 35 bricks, I employ a plurality of the transverse arch tubes, 18. The upper portions of these arch tubes provide seats or bearings for the ends of the bricks, 19. The ends of the bricks are preferably socketed to fit the 40 tubes in now well-known manner. The tubes, 18, occupy parallel vertical planes. They are arranged in intersecting pairs and are spaced apart, as required, to admit the spans or bricks, 19. The tubes of each pair 45 preferably occupy the same vertical plane, this arrangement being made possible by the non-interfering intersection portions or lateral bends, 18', in one or both tubes, as shown best in Fig. 4. By means of the bend, or 50 bends, the tubes are permitted to pass one another without interference and the upper portions, 18'', are allowed to occupy the same vertical plane; in other words, may be arranged in alignment crosswise of the firebox. 55

As clearly shown in Fig. 2, the tubes, 18, connect opposite side water legs, 8, 8, of the boiler; and to insure the rapid circulation of the water through the arch tubes, as required to preserve them each tube is inclined. Thus each tube is secured at a low point, 20, in one side sheet, 5, and rises to a high point, 21, in the opposite side sheet. Short bends, 18'', formed in the ends of the tubes 65 allow them to perpendicularly enter respec-

tive side sheets. The clearance between the grate and the lower portions of the tubes is preferably increased by an upward bend, 18'', in each tube. The tops, 18'', of the several tubes are preferably straight, as that 70 form provides the best seats for the firebricks, 19.

The bricks, 19, are of a single pattern, that is, they are all alike. In constructing the arch, I first place the bricks upon the 75 tubes and against the side sheets, 5, and then add other bricks toward the middle line of the fire box. Close joints with the side sheets are thus insured, and a tolerance space, 22, remains between the sides of the 80 middle pair of bricks in each transverse row. These tolerance spaces may be left open without objection, or closed; as by means of V-shaped gap-bricks, 23.

I have not attempted to show the component bricks of the wall, 17. I prefer that the wall shall always contain a clean-out opening, 17', through which the combustion 85 chamber, B, may be reached.

The wall has one special characteristic 90 which is novel. I refer to the form of the top of the wall, best shown in Fig. 1. Said top is provided with a middle top-portion, 17^a, and symmetrical bearing portions, 17^b, which take their shape from the shape of the 95 ends of the bricks, 19, that abut thereon. In this manner the wall is made to serve as an abutment and a bearing for the bricks composing the front row of the arch.

While I prefer the construction illustrated in Figs. 1 to 4, I nevertheless desire 100 that it shall be understood that my invention comprehends an arrangement in which the arch tubes do not contain the non-interfering bends, 18'. The modification referred 105 to is disclosed in Figs. 5, 6, and 7; from which it will be seen that by staggering the transverse tubes, 24, they may still be made to accommodate transverse rows of arch 110 bricks, 25. But in this, one row of short 115 bricks, 26, must be employed. Except in this short row, all of the other bricks may be the same throughout the arch.

To those who are skilled in the art it will 115 be apparent that by means of the construction here shown and described, shallow locomotive fireboxes may be successfully fitted with baffle walls which are quite as effective as the simpler corresponding constructions generally used in deep bituminous coal-burning locomotive furnaces. While the 120 construction described is adapted for use in barrel combustion chamber fireboxes of many different types, it unquestionably attains its greatest utility in fireboxes of the 125 Wooten type.

Having thus described my invention, I claim as new and desire to secure by Letters Patent:—

1. The improvement herein described, 130

comprising a locomotive firebox, in combination with a cross wall therein rearward of its flue sheet and forward of its grate, and an overhanging arch extending rearwardly from said wall and composed of a plurality of transverse rows of bricks together with a plurality of longitudinally spaced pairs of oppositely inclined transverse water-circulating arch tubes which connect the side sheets of the firebox and support said bricks. 5

10 2. The improvement herein described, comprising a locomotive firebox, in combination with a cross wall therein rearward of

its flue sheet and forward of its grate, and 15 an overhanging arch extending rearwardly from said wall and composed of a plurality of transverse rows of bricks together with a plurality of longitudinally spaced pairs of oppositely inclined transverse water-circulating arch tubes which connect the side sheets of the firebox and support said bricks, the tubes of each said pair being in a single vertical plane and offset at the middle to avoid the intersection of one by the other. 20 25

In testimony whereof, I have hereunto set my hand this 9 day of February, 1916.

JOHN P. NEFF.
